UNITED STATES PATENT OFFICE

2,263,951

HOIST

Edward Liechty, Fort Wayne, Ind.

Application April 3, 1941, Serial No. 386,713

1 Claim. (Cl. 214—108)

This invention relates to new and useful improvements in hoists intended to handle cardboard, paper, metal and any other material used in printing, box making, lithographing and allied arts.

The principal object of the present invention is to provide a hoist whereby all materials formerly handled by hand are now moved automatically without any manual effort, thereby immensely accelerating production.

Another important object of the invention is to provide a hoist of the character stated whereby loads can be trucked into the hoisting apparatus thereby eliminating the necessity of re-piling materials.

Other important objects and advantages of the invention will become apparent to the reader of the following specification.

In the drawings:

Figure 1 represents a front elevational view of 20 the apparatus.

Figure 2 is a side elevational view.

Figure 3 is a cross sectional view showing one of the rail attaching members.

Figure 4 is a fragmentary top plan view.

Figure 5 is a cross sectional view taken substantially on the line 5—5 of Figure 6.

Figure 6 is a sectional view taken substantially on the line 6-6 of Figure 5.

Figure 7 is a sectional view taken substantially 30 on the line 7—7 of Figure 5.

Referring to the drawings wherein like numerals designate like parts, it can be seen that the apparatus includes a pair of inclined eye beams 5 which extend upwardly from floor plates 6 to a machine table 7. A bar 8 connects the lower portions of the beams 5, 5 and rising from this bar 8 are spaced guide slats 9 extending upwardly and backwardly over the machine part 1.

The carriage part of the hoist consists of a pair of I beams 10, 10 which have spring strip bumpers 11 on the bottom thereof to withstand shock when the same are lowered onto the floor. These beams 10 are connected by chains 12. Observing Figure 2, it can be seen that a truck 13 can be moved into position with edge portions of its platform overlapping the rails or beams 10, 10.

The upper flanges of these beams 10 are formed with recesses 14. A double hook member 15 is provided for each end of each of the bars 10 and embraces the upper flange thereof, and each of these double hook members 15 has a swingable latch member 16 engageable into the corresponding notch 14 to prevent accidental shifting of the double hook member on the corresponding bar 10. A connector 17 is provided between each hook member 15 and a corresponding lift chain 18.

Forwardly inclined I beams 19 extend from the intermediate portion of each of the beams 5 and these beams 19 have upstanding members

20 on which are bearings 21, complementary to bearings 22 on the upper ends of the beams 5. These bearings 21 and 22 accommodate the forward and rearward ends of shafts 23 and 24. 5 On each of these shafts 23 and 24 is a pair of chain pulleys 25 over which the corresponding chain 18 is trained and the free end of each of these chains 18 is provided with a handle 26. The pulleys 25 are suitably keyed through hubs 10 27, as shown in Figure 5 denoted by the numeral 28 to the shafts 23 and 24. Each of the pulleys 25 has a guard housing 29 circumscribing the same and provided with guide tubes 30 and 31 depending therefrom for guiding the two flights 15 of the chain, these guides 30 and 31 being of cross shape in cross section, defining cross-shaped passageways for the links of the chains 18. The guides 30 and 31 have tail portions 32 which are attached to cross bars 33 bridging the upper ends 20 of the beams 5 with the members 20.

25 Mounted on the upper portion of one of the inclined beams 19 is an electric motor 34 having an armature shaft on which is a pinion 35. Mounted upon the upper portions of the members 12 are plates 36 having bearing formations 37 through which a shaft 38 is trained. The end portions of this shaft 38 have worms 39, 40 which mesh with overlying gears 41, 42 on the shafts 23 and 24, respectively.

30 One end of the shaft 38 has a sprocket wheel 43 and a sprocket chain 44 is trained over this sprocket wheel and the pinion 35.

Obviously, a truck 13 can be driven over the beams 10 while they are lying flat on the floor, 35 after which the hooks 15 can be engaged with the beams 10, this being done by the trucker, after which the motors 34 can be controlled by the pressman from a remote point.

40 While the foregoing specification sets forth the invention in specific terms, it is to be understood that numerous changes in the shape, size and materials may be resorted to without departing from the spirit and scope of the invention as claimed hereinafter.

45 Having described the invention, what is claimed as new is:

A hoist of the character described comprising substantially upright beams, a pair of shafts at the upper ends of the beams, drive means for the shafts, pulleys on the shafts, lines trained over the pulleys and structure engageable beams to which the lower ends of the lines are attachable, and detachable means for attaching the lower ends of the lines to the beams, said beams being of I-shape in cross section, said detachable means consisting of a double hook for each of the lines for embracing the upper flanges of the corresponding beam, said beams having notches therein, said double hook members having detents thereon for engagement in the notches.

SEARCHES IN THE NOTCHES.
EDWARD LIECHTY.
